Primary Examiner — R. Johnson(57) CLAIM

The ornamental design for a plectrum clip as shown and described.

DESCRIPTION

FIG. 1 is a top, right perspective view of a plectrum clip, showing the first embodiment of my new design; FIG. 2 is a bottom, left perspective view thereof; FIG. 3 is a top plan view thereof; FIG. 4 is a bottom plan view thereof; FIG. 5 is a front elevational view thereof; FIG. 6 is a rear elevational view thereof; FIG. 7 is a left side view thereof; FIG. 8 is a top, left perspective view of a plectrum clip, the plectrum clip shown as used, secured to a guitar strap and holding a plectrum; FIG. 9 is a top view thereof; FIG. 10 is a top, right perspective view of a plectrum clip showing the second embodiment of my new design; FIG. 11 is a bottom, left perspective view thereof; FIG. 12 is a top plan view thereof; FIG. 13 is a bottom plan view thereof; and, FIG. 14 is a left side view thereof.

In FIGS. 8 and 9, the evenly spaced broken lines represent environmental structure and form no part of the claimed design. The dot-dashed broken lines in FIGS. 10-14 represent a symbolic break in the length of the plectrum clip. The appearance of any portion of the article between the break lines forms no part of the claimed design.
